UNITED STATES PATENT OFFICE.

CHRISTOPHER AHRENS, OF CINCINNATI, OHIO, ASSIGNOR TO THE AHRENS MANUFACTURING COMPANY, OF SAME PLACE.

PUMP-VALVE.

SPECIFICATION forming part of Letters Patent No. 292,396, dated January 22, 1884.

Application filed June 2, 1883. (No model.)

To all whom it may concern:

Be it known that I, CHRISTOPHER AHRENS, of Cincinnati, in the county of Hamilton and State of Ohio, have invented certain new and useful Improvements in Pump-Valves, of which the following is a specification.

My invention is in the nature of an improvement upon the metal springs employed for "seating" pump-valves, and has for its object the construction of such springs of a form calculated to secure a more uniform resistance to the lift of the valve as it rises from its seat than can be obtained with the springs for such purposes heretofore in use.

In the accompanying drawings, Figure 1 is an elevation of an ordinary pump-valve, with the rubber disk shown in section. Fig. 2 is an elevation, and Fig. 3 a plan, of my improved spring. Figs. 4 and 5 are elevations of the two general styles of springs for this purpose previously employed.

Similar letters of reference indicate similar parts.

A is the customary metal grate or seat for pump-valves, provided with the central spindle, B, which guides the valve or disk and limits the upward motion thereof by means of the collar b.

C is the disk or valve, usually of rubber, as shown in Fig. 1, and provided with the central orifice, which is large enough to permit the disk to slide freely up and down the spindle B.

D is my improved spring, consisting of successive coils d d, from the lower or larger one of which the projection d' enters a corresponding aperture in the rubber disk C, to prevent the spring from revolving on and chafing the rubber.

As will be observed, the spring D is of several coils of regularly-diminishing diameter from the bottom to top; and the two upper or smaller coils, d d', are wound the one within the other, so as to occupy the same plane, and form a seat or shoulder to bear against the under side of collar b.

By reference to Fig. 3, the horizontal plan of the spring is such that as it is compressed

by the lift of the valve, as shown in dotted lines of Fig. 1, the several coils collapse in a ratio inversely as the diameters thereof, whereby the entire spring is brought into action for any degree of lift of disk C, and for any ordinary lift the increase in the resistance of the spring is inappreciable in practice. Fig. 4 exhibits an ordinary spiral spring, which for the short length necessary for this purpose, as shown by the space between the disk C and collar b of Fig. 1, which is an exact representation, full size, of a valve for the pump of a steam fire-engine, rapidly increases in power or resistance as the disk C rises from its seat, and consumes (where there are many valves, as is usual in the construction of pumps at the present time) a large percentage of the engine-power in forcing the valve from its seat.

Fig. 5 is an ordinary volute spring, the kind in most general use for seating pump-valves, and possessed, though in a smaller degree, of the objectionable features of the spiral spring, Fig. 4, but lacking in the essential quality of springs for this purpose—viz., the uniformity of load imposed upon disk C for an ordinary lift or opening of valve.

The distinguishing difference in construction of my improved spring, Figs. 2 and 3, and the common volute spring, Fig. 5, is that in the former the two upper coils, d d', are wound in the same plane, the latter within the former, while in the volute spring the figure in section is a true cone; nor am I aware of the use for any purpose of a spring such as I have described and shown in Figs. 2 and 3.

I am aware that springs for seating pump-valves are in common use, and that springs as shown in Figs. 4 and 5 are old and well known in the arts. These I do not claim.

Having described my invention, what I claim is—

The combination of a valve-seat, A, having the central spindle, B, provided with the stationary collar b, and the valve C, arranged to rise and fall on the spindle, with the spring D, composed of the successive coils d, of uni-

uniformly-diminishing diameter from the base, the extremity of the lower coil having the projection d entering an aperture in the valve, and the two upper coils wound one within

In testimony whereof I have signed my name to the foregoing specification in the presence of two subscribing witnesses. CHRISTOPHER AHRENS. Witnesses: JOHN W. HILL, JOSEPH W. SIMS.
